CLAIM

The ornamental design for a cosmetic tube, as shown and described.

DESCRIPTION

FIG. 1 is a front elevational view of our cosmetic tube;
FIG. 2 is a rear elevational view thereof;
FIG. 3 is a right side view thereof;
FIG. 4 is a left side view thereof;
FIG. 5 is a top plan view thereof;
FIG. 6 is a bottom plan view thereof;
FIG. 7 is a view similar to that of FIG. 1, but with the cap removed; and,
FIG. 8 is a cross-sectional view taken along the line 8—8 of FIG. 1.
